AMPLIFYING STETHOSCOPE

Joseph Weinstein, Brooklyn, N. Y.

Application February 2, 1935, Serial No. 4,697

1 Claim. (Cl. 179—171)

This invention relates to electrically amplifying stethoscopes such as are shown in my prior Patent No. 1,976,707 of October 9, 1934 and more especially relates to improvements in the circuits and arrangements of parts shown and described in the aforesaid patent.

One important object of the invention is to improve the sensitivity of devices of this character.

10 A second important object of the invention is to provide, in such a device, a simple and efficient volume control for such stethoscopes.

A third important object of the invention is to provide a separate choke coil for the output of 15 such instruments.

A fourth important object of the invention is to provide an improved amplifying stethoscope wherein amplification will be effected without the use of a transformer.

20 With the above and other objects in view, the invention consists in general of certain novel circuit arrangements and combinations of details hereinafter fully described and claimed, one embodiment of the circuits and apparatus used being illustrated in the accompanying drawing, 25 wherein:

The figure is a wiring diagram of the complete device.

In the embodiment of the invention shown in 30 the accompanying drawing there is provided a combined stethoscopic sound receiver and microphone or microphonic stethoscope 10 from which leads a cable 11 of the usual two wire type, one wire being connected to a contact 12 and the other 35 wire being connected to a contact 13. A shield 14 surrounds at least a portion of the cable adjacent the contacts, the latter being supported by said shield. A jack having spring contacts 15 and 16 is provided to receive the contacts 12 and 40 13 so that they engage respectively with the said jack contacts. A conductor 17 leads from the contact 15 to a ground 18 and a conductor 19 leads from the contact 16 through a 1 megohm resistance 20 and is connected to the ground wire 17. 45 Also a conductor 21 leads from the contact 16 to the grid 22 of a vacuum tube 23 which also contains a plate 24, a cathode 25 and a heater filament 26. The conductor 21 is preferably covered by a shield 27.

50 The cathode 25 is connected by a conductor 28 with one terminal of a 10 megohm resistance 29 which in turn has its remaining terminal connected through a conductor 30 with the ground 55 wire 17. A 1 microfarad condenser 31 is con-

nected by conductors 32 and 33 with the respective conductors 28 and 30, the resistance 29 and condenser 31 being thus connected in parallel between the cathode 25 and ground 18.

A conductor 34 connects the plate 24 with one end of a choke coil 35 having its other end connected by a conductor 36 with a ground 37 through a condenser 38. The choke coil has a grounded core 39 and forms what is termed an audio choke. A 1 megohm resistance winding 40 has one end 10 connected to the conductor 34 by a conductor 41 and its other end connected to the conductor 36, between the condenser 38 and coil 35, by a conductor 42. The audio choke 35 and resistance 40 are thus connected in parallel between the 15 plate 24 and ground 37.

Movable over the windings of the resistance 40 is a contact 43 which is connected by a conductor 44 with a 0.2 microfarad condenser 45. At 46 is a vacuum tube having a grid 47, a plate 48 shielded 20 by a pair of parallel connected grids 49, a cathode 50 carrying a fourth grid 51 and a heater filament 52. The condenser 45 is connected by a conductor 53 with the grid 47. The conductor 53 is connected by a conductor 54 with one end of a 500 25 megohm resistance 55 having its other end connected by a conductor 56 with a ground 57.

The cathode 50 is connected by a conductor 58 with a 5 megohm resistance 59 having its other end connected by a conductor 60 to the ground 30 wire 56. A 1 microfarad condenser 61 is connected by a conductor 62 with the conductor 58 and by a conductor 63 with the ground wire 56, the resistance 55 and condenser 61 being thus connected in parallel between the cathode 50 and 35 ground 57. The grids 49 are connected by a conductor 64 with a source 65 of 22½ volt current and a 0.5 microfarad condenser 66 is bridged across between the conductors 52 and 64.

The plate 48 is connected by a conductor 67 40 and a 0.5 microfarad condenser 68. A conductor 69 connects the conductor 67 with one end of a choke coil 70 having its other end connected by a conductor 71 with one end of a 20 megohm resistance 72. The other end of the resistance 72 45 is connected by a conductor 73 to the conductor 36 between the condenser 38 and coil 35 so that the coil 70 is grounded through the resistance 72 and condenser 38. The choke coil has its core 74 grounded and forms an audio choke for 50 the tube 46.

At 75 is a third vacuum tube having a grid 76, plate 77, cathode 78 and heater filament 79. A conductor 80 connects the condenser 68 with the grid 76 and this conductor is connected by 55

a conductor 81 with one end of a 500 megohm resistance 82 having its other end grounded through a conductor 83. The cathode 78 is connected by a conductor 84 with one end of a 2 megohm resistance 85 having its other end connected by a conductor 86 with the ground wire 83. A 1 microfarad condenser 87 is connected by a conductor 88 with the conductor 84 and by a conductor 89 with the conductor 86 so that the resistance 85 and condenser 87 are connected in parallel between the cathode 78 and the ground. The plate 77 is connected by a conductor 90 with a 0.5 microfarad condenser 91, this condenser being connected by a conductor 92 with an output terminal 93. The other output terminal 94 is connected by a conductor 95 with the conductor 88. A 30 Henry choke coil 96 has one end connected to the conductor 90 by a conductor 97 and its other end connected by a conductor 98 to the positive terminal 99 of a connection for 135 volt current. The negative terminal 100 for this current is grounded through a conductor 101.

Six volt heater terminals 102 are connected by conductors 103 to the heater filaments of the several tubes so that such filaments are connected in multiple.

In use, the microphonic stethoscope is applied to a portion of the anatomy over the organ to be auscultated, one or more sets of telephone ear pieces having been connected to the output terminals. Then the sound impulses emanating from the organ are translated into electrical impulses through the action of the microphone, amplified by the amplifier, and received through the ear pieces as amplified sounds. Obviously a loud speaker device may be connected to the out-put terminals if desired and, when arranged in this manner, the apparatus may be used for clinical demonstrations.

It will be observed that adjustment of the contact 43 along the resistance 40 controls the input to the grid of the second tube and thereby controls the volume delivered to the output terminals of the device. By this means faint sounds may be amplified to clearness while loud sounds may have their amplification restricted so as not to be unpleasant to the auditor.

There has thus been provided a simple and efficient device of the kind described and for the purpose specified.

It is obvious that changes may be made in the arrangement of the parts without departing from the spirit of the invention. It is not, therefore, desired to confine the invention to the exact ar-

rangement here shown, but it is desired to include all such as come within the scope of the appended claim.

What is claimed is:—

An amplifying instrument for microphonic stethoscope circuits comprising in-put terminals, a set of three electronic vacuum tubes each having a grid, a plate, a cathode and a heater element, the middle tube of said set further having a pair of grids between which the plate of said tube is located, a conductive connection between one of said terminals and the grid of the first tube, a ground connection from the other terminal, a resistance bridged between said terminals, a conductive connection having a resistance 5 therein and connecting the cathode of the first tube to the ground, a condenser bridged between the terminals of the last resistance, a choke coil and a third resistance conductively connected in multiple to the plate of the first tube and connected to the ground through a second condenser, a connection from the grid of the second tube to the third resistance through a condenser and arranged for variable connection to said third resistance, a resistance providing ground connection to the last connection between the grid and condenser of said last connection, a resistance providing ground for the cathode of the second tube and having a condenser bridged around the resistance therein, a conductive power input 10 connection for said pair of grids, a condenser bridged between said power input connection and the ground from the second cathode, a connection between the plate of the second tube and the grid of the third tube, a choke coil having one terminal conductively connected to the plate of the second tube and its other terminal connected conductively to the second condenser through a resistance, a conductive ground connection for the grid of the third tube including a resistance, 15 a conductive ground connection for the cathode of the third tube and having a condenser bridged around its resistance, an output terminal conductively connected to the last connection between the cathode and its grounding resistance, a second out-put terminal, a connection between the plate of the third tube and the second out-put terminal, a choke coil having one end conductively connected to the last plate and its other end conductively connected to the corresponding end of the second choke coil, a power in-put connection supplying current to said plates through said choke coils, and a heater circuit for said heaters.

JOSEPH WEINSTEIN. 55
